His Attorney.

UNITED STATES PATENT OFFICE.

STEPHEN H. JONES, OF LOWELL, MASSACHUSETTS.

LET-OFF MECHANISM FOR LOOMS.

SPECIFICATION forming part of Letters Patent No. 289,420, dated December 4, 1883.

Application filed September 25, 1879.

To all whom it may concern:

Be it known that I, STEPHEN H. JONES, of Lowell, in the county of Middlesex and Commonwealth of Massachusetts, have invented a new and useful Improvement in Let-Off Mechanisms for Looms, of which the following is a specification.

My invention consists in the combination of a pinion, two differential gears, one of said gears being fixed and the other being secured to the beam-pinion shaft, said shaft, the beam-pinion, the beam-gear, the ratchet, a lever provided with a pawl, a connecting-rod, and another lever adapted to be actuated by the motion of the sword of the lay, that being the specific means for accomplishing the motion of the warp-beam; also, in the combination of a pinion, two differential gears, one of said gears being fixed and the other being secured to the beam-pinion shaft, said shaft, the beam-pinion, the beam-gear, the ratchet, the lever first-mentioned provided with a pawl, another lever, a connecting-rod, another rod, and the whip-roll provided with an arm, to bring the pawl forward and to place said last-mentioned lever in a position to be actuated by the sword of the lay; also, in the combination of a hand-wheel, a pinion, two differential gears, one of said gears being fixed and the other being secured to the beam-pinion shaft, said shaft, the beam-pinion, the beam-gear, and the ratchet, to enable the warps to be tightened or loosened by hand.

In the accompanying drawings, Figure 1 is a side elevation of a loom-frame, to which my invention is attached; and Fig. 2 is an end elevation of the same, the take-up mechanism being partly shown in Fig. 1.

A is the frame; B, the yarn-beam, provided with the gear C, secured to the head and concentric with it; D, the whip-roll, provided with a longitudinal rib or projection; E, the whip-roll arm, secured to the end of the shaft of the whip-roll; F, the tension-spring rod, the rear end (the right-hand end in Fig. 1) of which is pivoted to the lower end of the arm E and the other end of which rod slides in a bracket, Z, on the loom-frame; G, the tension-spring on the rod F, between the bracket Z and the collar H; H, the collar on the rod F, set by a screw (which passes through one side of the

collar and pinches the rod) at such a distance from the arm E as to insure the requisite resistance to the forward motion of said arm and thereby to secure the proper amount of 55 tension on the warps X, passing over the whip-roll D from the yarn-beam B; I, the lever, against the upper end of which the front end of the rod F strikes when the tension of the warps over the rib of the whip-roll is sufficient to throw the arm E forward, said lever being pivoted a little below its upper end, and being bent forward at its lower end and passing between the hook K and the frame A, and being then bent out at right angles to said 60 frame in front of said hook; K, the hook on the sword J of the lay, being a rod standing out from the sword and bent up nearly parallel with the sword on the outside of the frame. The take-up motion consists of a ratchet, T, and impelling-pawl T', operated by an eccentric on the crank-shaft Y, a retaining-pawl, T", and a series of gears (one of which is attached to the sand-roll and another of which turns with the ratchet T) and the cloth-beam, the object of the take-up being to roll 65 the cloth as fast as it is woven on the cloth-beam. All of the parts named in the above 70 description are the same as commonly used.

L is the beam-pinion stand, secured to the 75 frame A and supporting the beam-pinion shaft M, (shown by dotted lines, Fig. 2,) which runs parallel to the yarn-beam B. On the inner end of the shaft M is secured the beam-pinion N, which takes into the gear C. These 80 parts are also old.

Around the shaft M is the stationary gear O, fixed to the stand L, or cast in one piece with it, or otherwise prevented from turning. The gear O' is fast to the shaft M, and has more 85 teeth than the gear O, (say fourteen teeth on the gear O' to twelve teeth on the gear O for ordinary work; for finer work, one tooth less on the gear O than on the gear O';) but these gears O O' are of the same diameter. The 90 ratchet-wheel P is loose on the shaft M, and is provided with a hub on its outer face. The lever Q, carrying the pawl R, which impels the ratchet P, is loose on the hub of said ratchet P. To the inner face of said ratchet P is secured a stud, V, (parallel with the shaft M,) 95 which carries a pinion, S, which pinion takes 100

into the two gears O O'. It will be seen that if the ratchet P be turned in the direction of its arrow, the pinion S will roll around the differential gears O O', and as the gear O' has a greater number of teeth than the stationary gear O, the gear O' will be revolved slowly in the same direction as the ratchet P, the pinion S "evening" the teeth of the gears O O' and causing the gear O' to advance with one revolution of the ratchet P as many teeth as the gear O' has in excess of the gear O. Thus the revolution of the ratchet P revolves the shaft M, to which the gear O' is fixed, and the pinion N, causing the yarn-beam B to revolve in the opposite direction, and thereby unwinding the warps from the yarn-beam. The lower end of the lever Q is connected by the rod U to the lower end of the lever I, so that when the tension of the warps (the line X, Fig. 1, representing at its left-hand end cloth and at its right-hand end warps) is sufficient to throw the upper end of the lever I forward—that is, to the left in Fig. 1—as hereinbefore explained, the lower end of said lever I will be thrown back toward the ratchet P, bringing the upper end of the lever Q with the pawl R forward. When the lever I is in this position the next stroke (forward) of the lay will cause the hook K to knock the lower end of the lever I forward, and the pawl R, consequently, backward, turning the ratchet P and unwinding the warps from the yarn-beam. A hand-wheel, W, fastened to the hub of the ratchet, enables the shaft M to be turned by hand when necessary.

Heretofore it has been necessary to use a friction device to prevent the action of the lay from pulling the warps too rapidly from the yarn-beam; but it will be seen that no amount of force applied to the warps or to the yarn-beam, or even to the beam-pinion or its shaft,

will be sufficient to turn said shaft without breaking some of the parts, as said shaft cannot be moved except by the ratchet carrying the stud-pinion S around the differential gears, inasmuch as at least one tooth of the pinion S always lies like a rigid bar dropped between two teeth on each of the differential gears; hence the warps will not be let off the yarn-beam except as the motion of the ratchet P lets them off.

I claim as my invention—

1. The combination of the pinion S, the differential gears O O', one of said gears, O, being fixed and the other, O', being secured to the beam-pinion shaft M, said shaft M, the beam-pinion N, the beam-gear C, the ratchet P, the lever Q, provided with the pawl R, the connecting-rod U, and the lever I, adapted to be actuated by the motion of the sword of the lay, as and for the purpose specified.

2. The combination of the pinion S, the differential gears O O', one of said gears, O, being fixed and the other, O', being secured to the beam-pinion shaft M, said shaft M, the beam-pinion N, the beam-gear C, the ratchet P, the lever Q, provided with the pawl R, the lever I, the connecting-rod U, the rod F, and the whip-roll D, provided with the arm E, as and for the purpose specified.

3. The combination of the hand-wheel W, the pinion S, the differential gears O O', one of said gears, O, being fixed and the other, O', being secured to the beam-pinion shaft M, said shaft M, the beam-pinion N, the beam-gear C, and the ratchet P, as and for the purpose specified.

STEPHEN H. JONES.
